US00D564177S

(12) **United States Design Patent** (10) **Patent No.:** **US D564,177 S**
Edwards et al. (45) **Date of Patent:** **** Mar. 18, 2008**

(54) **LION DESIGN FOR FOOD PRODUCTS**

(75) Inventors: **John B. Edwards**, Battle Creek, MI (US); **Karla K. Norstrom**, Battle Creek, MI (US); **David Keith Tebow**, Battle Creek, MI (US); **Charles Gambino**, Kalamazoo, MI (US)

(73) Assignee: **Kellogg Company**, Battle Creek, MI (US)

(**) Term: **14 Years**

(21) Appl. No.: **29/279,961**

(22) Filed: **May 11, 2007**

(51) **LOC (8) Cl.** **01-01**

(52) **U.S. Cl.** **D1/109**

(58) **Field of Classification Search** D1/106-15, D1/120, 126-9, 199; D28/8.2; D24/102; 426/94-5, 89, 104, 138-9, 144, 543, 549-50, 426/383, 496

(57) **CLAIM**

We claim the ornamental design for the lion design for food products, as shown and described.

DESCRIPTION

FIG. 1 is a top plan view of the lion design for food products of the present invention.

FIG. 2 is a rear elevation view of the lion design for food products of the present invention.

FIG. 3 is a left side elevation view of the lion design for food products of the present invention.

FIG. 4 is a right side elevation view of the lion design for food products of the present invention; and,

FIG. 5 is a front elevation view of the lion design for food products of the present invention.
